UNITED STATES PATENT OFFICE

DAVID FORSTER FOUTZ, OF BALTIMORE, MARYLAND

RADIATOR CONDENSER

Application filed September 25, 1928. Serial No. 308,298.

This invention relates to an improvement in radiators of that type involving a condenser included within the body of the radiator and utilized in a system such as described in connection with an application of Clinton R. Foutz, filed July 16, 1928, Serial No. 292,991.

In constructions wherein the condenser is built in as a part of the radiator proper and indistinguishable therefrom in appearance, it is important that the condenser, which must be open to the upper water header in the operation of the system, should be temporarily closed against that header during the filling of the system with water in order to avoid delivery of water into the condenser, with the well understood disadvantages.

In connection with the system described, it is important that the filling opening by which water is introduced into the system be sealed against the admission of air, and as the water cannot be introduced into the system except through this filling opening, it is advisable from a practical standpoint to utilize the cap for the filling opening as the means for governing the circulatory relation of the upper header and the condenser.

The primary object of the present invention, therefore, is to provide an opening leading to the condenser and communicating with the upper header and provide means which, when the filling cap is in place, will maintain this opening in condition for free communication between the header and condenser and when the filling cap is removed, cause the opening to be automatically closed.

More specifically, the invention consists in providing a tubular member opening from the condenser header and into the radiator header, a valve being arranged to automatically close this opening to cut off communication between the condenser and radiator header when the filler cap is removed, with means carried by the cap for maintaining the valve in open position to establish communication between the condenser and radiator header when the filling cap is in place.

The invention is illustrated in the accompanying drawings, in which:

Figure 1 is a broken view in elevation,

partly in section, illustrating a preferred type of radiator wherein the condenser forms a part of the radiator body.

Figure 2 is a section on line 2-2 of Figure 1.

In the particular form of radiator illustrated, the upper header 1 of the radiator 2 has its lower wall defined by a plate 3 from which tubes 4 depend to a similar plate of the lower header (not shown), the tubes 4 forming the circulatory communication between the upper and lower headers, as is usual. The special form of tube here illustrated is not claimed as a part of this invention, and while preferred is not important in the invention to which the present application is directed, whereby it will be understood that any type of tube may be used without departing from the spirit of the present invention.

In this form of radiator a plate 5 overlying the plate 3 and secured at its side edges to the plate 3 immediately adjacent the side walls of the header and having end walls 6 secured to the plate 3 defines an upper condenser header 7 with which the condenser tubes 8 communicate, it being understood that such tubes lead from the upper condenser header to the lower condenser header. It is to be understood that the construction contemplates a lower condenser header substantially similar in all respects to the described construction of the upper condenser header, such lower condenser header being, therefore, unnecessary to illustrate.

The radiator header 1 is provided with a filling tube 9 through which water may be introduced for the purpose of filling the system, this tube having an inwardly arranged annular flange 10 to receive a sealing disk 11 carried by the filling cap 12 which has threaded connection at 13 with the upper end of the tube 9. Suitable packing 14 may be introduced between the disk 11 and the upper edge of the flange 10 to insure that the cap when in place seals the filling opening against the admission of air.

The vapor, steam and initially the air contained in the cooling fluid will collect in the upper header and is to be directed through the condenser and redelivered to the cooling fluid.

beyond the delivery end of the lower header in the system. To provide for the entrance of this vapor and the like into the condenser, the latter is provided with an upstanding inlet tube 15 of materially less diameter than the filling tube, the upper end of the inlet tube 15 extending somewhat into the filling tube. It is to be understood, though unnecessary to illustrate, that conventional means are provided for delivering the condensate from the lower condenser header into the cooling fluid, with the result that the vapor which collects above the upper condenser header and above the cooling fluid in the radiator proper is delivered through the tube 15 into the upper condenser header, into the cooling tubes 8 in communication with said upper condenser header, and condensed to collect as water in the lower condenser header, from which it is forced under conventional means, as referred to, into the circulatory path of the cooling fluid.

The upper and lower ends of the tube 15 are provided with disks 16 which are freely perforated at 17 to permit the passage of vapor therethrough, the upper disk 16 being removable, if desired, through the threaded connection 16' to provide access to the valve parts. A valve rod 18 is mounted for sliding movement in the disks 16 and extends above the upper disk. A valve 19 is secured upon this rod and a spring 20 is coiled about the rod between the valve and the lower disk to insure that, when free to move, the valve 35 will be moved into a position to close the openings 17 in the upper disk 16 and thereby seal the condenser against the radiator header. The filling cap 12 is formed with a depending column 21, preferably notched at its 40 lower end as at 22, to cooperate with the upper preferably pointed end 23 of the valve rod 18.

The relation of the parts is such that when the cap 12 is in place, the column 21 will 45 bear upon and depress the valve rod 18 against the tension of the spring 20 to a degree to permit the valve to be moved away from the openings 17 in the upper disk 16 and thereby establish free communication 50 between the radiator header and the condenser. Obviously, on removal of the cap for the purpose of delivering water into the system, the spring 20 acts to cause the valve to move to a position to close the opening 55 in the upper disk 16. Therefore, as long as the filling cap is in place, free communication is established between the radiator header and the condenser, while on removal of the cap for any purpose the condenser is immediately closed against the radiator header.

If desired, a deflector disk 24 may be secured to the inlet tube 15 of the condenser to direct the incoming water away from such tube.

The disk 11 of the sealing cap has free edge to permit a more or less spring effect in forcing the latter into and maintaining sealing effect with the packing 14.

It is to be understood that as described the combined radiator and condenser has the 70 general external appearance of a conventional radiator in which the upper and lower headers are connected by tubes open to the cooling influence of the air passing between them. For the present invention, however, the central group of these tubes are closed against the upper and lower headers of the radiator proper by plates which overlie and underlie the ends of this central group of tubes and so prevent the water in the radiator header from passing through this central group of tubes. This central group of tubes constitutes the condenser and is of course open to the cooling influence or heat exchange with the air passing between the tubes exactly as in the radiator proper. The condenser is open at the upper end to tube 15 and the latter, when the filler cap is in place, is open to the upper header of the radiator above the normal level of water therein. The lower end of the condenser has an outlet independent of the outlet from the radiator lower header.

The improved radiator condenser is used 95 in a system such as described in the application referred to above wherein, incident to the heating of the cooling fluid by the heat exchange with the walls of the cylinders, vapor collects on the surface of the water in the upper header chamber of the radiator. This vapor is directed through the condenser and condensed by the cooling influence of the air passing between and around the condenser tubes, and the condensate is returned 100 to the cooling fluid beyond the radiator, all as will be clear from the description of the system proper in the above noted application.

Thus, the unit, which has the appearance 110 of a conventional or more or less conventional radiator, is in fact a radiator and condenser combined, the condenser serving to condense the vapor produced incident to the heating of the cooling fluid by the engine, with the cooling influence on the condenser being the air passing between and around the tubes of the condenser in exactly the same manner in which the water in the radiator is cooled in its travel from the upper header to the lower header of the radiator.

What is claimed to be new is:

1. A radiator having a condenser formed as a part thereof, communicating means between the radiator header and condenser, and means governed by the position of the filler cap of the radiator for controlling said communicating means.
2. A radiator having a condenser formed as a part thereof, a valve for controlling 120

communication between the radiator and condenser, and means on the filler cap of the radiator and condenser, and means on the filler cap of the radiator for governing the position of the valve.

5 3. A radiator including a condenser formed as a part thereof, a valve for controlling communication between the radiator condenser and header, means for normally holding the valve in position to cut off such communication, a filler cap for the radiator filling opening, and means on the cap to hold the valve in open position when the cap is in place.

10 4. A radiator including an upper header, a filling tube leading thereto, a cap for the filling tube, a condenser formed as a part of the radiator, an inlet tube leading to the condenser and arranged within the header of the radiator, a valve cooperating with the open end of said tube, a spring normally holding the valve in closed position, and a column depending from the cap to force the valve to open position when the cap is in place.

15 5. A radiator including an upper header, a filling tube leading thereto, a cap for the filling tube, a condenser formed as a part of the radiator, an inlet tube leading to the condenser and arranged within the header of the radiator, an opening at each end of the inlet tube, a valve rod movable longitudinally of the inlet tube and extending above the same, a valve on said rod, a spring for 20 operating the valve to normally close the opening leading to the inlet tube, and a column depending from the filler cap to engage the end of the valve rod and hold said valve in open position when the filler cap is in place.

25 40 In testimony whereof I affix my signature.
DAVID FORSTER FOUTZ.
